JACOB P. TIRRELL, OF CHARLESTOWN, AND HIRAM WHITNEY, OF WATERTOWN, MASSACHUSETTS, ASSIGNEES, BY MESNE ASSIGNMENTS, TO HIRAM WHITNEY AND M. L. MARSHALL AND COMPANY.

Letters Patent No. 89,358, dated April 27, 1869.

IMPROVEMENT IN PAPER-FILES.

The Schedule referred to in these Letters Patent and making part of the same.

To all whom it may concern:

Be it known that we, JACOB P. TIRRELL, of Charlestown, county of Middlesex, and State of Massachusetts, and HIRAM WHITNEY, of Watertown, county and State aforesaid, have invented an improved Paper-File, and that the following is a full, clear, and exact description thereof, reference being had to the accompanying drawings, in which—

Figure 1 is a front view of our file.

Figure 2 is a back view of same.

The object of our invention is to produce a bill or paper-file which shall conveniently hold papers, while it presents means for computing accounts and making memoranda.

The nature of our invention consists in a board having a clamp held by springs, and a tablet and slate upon the back of the board.

In the drawings—

A is a board, of proper dimensions.

B, a clamp, or clasp. In fig. 1, this clamp B is shown as raised for the insertion of papers.

c and c' are wires running along the sides of board A, attached to the board at K K and m m.

A wire, b, is bent around wires c c', and extends over clasp B, and holds clasp B by staples S S, or equivalents.

The wire b is bent at b' over a hole in clasp B.

d d are wires bent around wires b b, at the side of the clamp B, and attached to board A, at the foot, the wires terminating in coil-springs d' d''.

h is a tongue, under bend b', to prevent too much action of wire b.

e is simply a ring, or staple, serving as a handle. The wires c c' are bent, as shown at K K.

Now, when the clamp B is drawn up, as shown in fig. 1, the wires b hold on the curve of wires c c' at K K, against the action of springs d d', but a slight pressure of wire b, at K, will relieve the hold of wire b, upon the bend at K, and the force of springs d' d'' upon wires b will bring the clamp B down upon the papers.

The advantage of this construction over others is that when the clasp B is down there are no wires and joints projecting from the board A, but all is smooth.

We put upon the back the erasable tablet D and slate surface F. The advantage of this is apparent, for collectors and others often want to make some memorandum, or cast up accounts, &c., and this gives the convenient means.

We attach loops i i, for holding pencils.

What we claim as our invention, and desire to secure by Letters Patent, is—

In combination, the board A, wires c c' b d, springs d d', and clasp B, the whole making a paper-file, substantially as described and specified.

In testimony whereof, we have signed our names to this specification, in the presence of two subscribing witnesses.

JACOB P. TIRRELL.
HIRAM WHITNEY.
